HOLDER FOR CANDLES, CHRISTMAS TREES, OR THE LIKE

Erik-Arne Lindroth, 37 Ostermovagen,
85002 Sundsvall, Sweden

Filed Jan. 6, 1969, Ser. No. 15,224

Claims priority, application Sweden July 4, 1968

Term of patent 14 years

Int. Cl. D11—02

U.S. Cl. D35—3

FIG. 2

FIG. 1 is a perspective view, showing in solid lines my new design for a holder for candles, Christmas trees, or the like, the tree or candle being shown in dotted outline;

FIG. 2 is a plan view of the holder; and

FIG. 3 is an elevation view of the holder.

The broken lines are for illustrative purposes only.

I claim:

The ornamental design for a holder for candles, Christmas trees, or the like, substantially as shown and described.
